Patent No. D465,517 S

Patented: November 12, 2002

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: David H. Brooks, Jr., Wilton, CT (US); Joseph B. Sugrue, Fairfield, CT (US); and David Beckstrom, Milford, CT (US).

Signed and Sealed this First Day of January 2008.
